UNITED STATES PATENT OFFICE.

RONALD ST. CLAIR CARTER, OF VANCOUVER, BRITISH COLUMBIA, CANADA.

ADVERTISING DEVICE.

1,385,665.

Specification of Letters Patent. Patented July 26, 1921.

Application filed July 15, 1920. Serial No. 396,380.

To all whom it may concern:

Be it known that I, RONALD ST. CLAIR CARTER, a subject of the King of Great Britain, and a resident of the city of Vancouver, 5 in the Province of British Columbia, Canada, have invented certain new and useful Improvements in Advertising Devices, of which the following is a specification.

My invention relates to improvements in 10 advertising devices, and the object of my invention is to provide a simply constructed, practical and efficient means whereby advertising matter may be displayed mechanically and in a highly attractive manner.

I attain this object by the construction 15 illustrated in the accompanying drawings in which—

Figure 1 is a back view of my device, the cover being removed.

Fig. 2 is a front view.

Fig. 3 is a sectional view taken on the line 3—3 of Fig. 1.

Fig. 4 is a sectional view taken on the line 4—4 of Fig. 1.

Fig. 5 is a sectional view taken on the line 5—5 of Fig. 1.

Similar figures of reference indicate similar parts throughout the several views.

1 indicates a box or casing in which the 30 mechanism hereinafter described is inclosed, the box having a glass front 2 behind which is placed a wood or metal partition 3 from which it will be seen that the box is divided into two compartments 4 and 5 the front 35 one 4 being inclosed by the glass front 2 and the partition 3 and the back one 5 being inclosed by the partition 3 and the back cover 6. The partition 3 is provided with one or more rectangular slots and in the 40 apparatus taken for illustration there are shown in Fig. 2, three such parallel rectangular slots 7, 8, and 9. The four rectangular sections into which the partition 3 is thus divided by the slots 7, 8 and 9 are interconnected by suitable brackets 3', as indicated in Figs. 1 and 3, the said brackets 45 serving to support the three inner sections from the outermost section, it being understood that the latter section is suitably secured to the sides and ends of the box or 50 casing 1. As shown to better advantage in Fig. 3, the said brackets 3' are U-shaped.

Suitably supported rotatably within the box 1 is a pulley 10 driven by a suitably lo-

cated motor (not shown) connected to the 55 pulley shaft 11 which pulley 10 is belt or rope connected to a larger sheave or pulley 12 having attached to it concentrically a pulley 13, which latter pulley is in turn belt or rope connected to a pulley 14 mounted on 60 a shaft 15 rotatably supported by a vertical support member 16 and the partition 3, on which shaft are secured side by side the small lower pulleys 17, 18 and 19 which are belt connected to companion pulleys 20, 21 65 and 22 secured to shafts 23, 24, and 25 rotatably carried by the support 16 and partition 3, these shafts being provided respectively with small pulleys 26, 27 and 28, around which passes endless belts 29, 30, and 70 31, these belts also passing around idler pulleys 32 which may be supported in any suitable manner and are positioned so that the belts move directly behind the respective slots 7, 8 and 9. At suitable intervals in 75 the belts are secured pins 33 which project through the slots to the front of the partition 3 and on these pins plates 34 are pivotally hung, the point of connection of each pin being slightly above the longitudinal 80 center line of the plate.

The manner in which the device operates and its utility will be apparent as it will be seen that when the motor pulley 10 is set in motion all the other pulleys will also be 85 rotated causing the plate carrying belts 29, 30, and 31 to travel along behind the slots in the partition so that the plates, which carry the advertising matter, will travel along in front of the partition longitudinally and vertically in an endless chain, as it were, and if the belts connecting lower pulleys 17 and 19 with upper pulleys 20 and 22 are crossed, the inner and outer belts will travel in a direction opposite to the 95 middle one. No driving mechanism being visible the device is very attractive and thus presents a means of displaying advertising matter in a highly efficient manner.

What I claim as my invention is:—

1. An advertising device comprising an upright rectangularly slotted partition, an endless belt arranged to travel behind and opposite said slot, and a plurality of advertising plates pivotally carried by said 105 belt disposed in front of said partition, the point of pivotal connection being above the horizontal center line of the plates.

2. An advertising device comprising a casing, an upright partition within the casing provided with a plurality of parallel rectangular slots contained one within the other, an endless belt for each slot arranged behind and opposite the same, pins secured to said belts at spaced intervals extending

horizontally through said slots to the front of said partition, advertising plates pivotally mounted on said pins, and means for driving said belts.

Signed at Vancouver, B. C., Canada, this 7th day of July, 1920.

RONALD ST. CLAIR CARTER.
